UNITED STATES PATENT OFFICE.

SAMUEL H. SHIMINSKY, OF NEW YORK, N. Y.

DESIGN FOR AN ELECTRIC-LIGHTING FIXTURE.

47,899.

Specification for Design.

Patented Sept. 28, 1915.

Application filed November 23, 1914. Serial No. 873,647. Term of patent 7 years.

To all whom it may concern:

Be it known that I, SAMUEL H. SHIMINSKY, a citizen of the United States, and a resident of New York, borough of Manhattan, in the county of New York and State of New York, have invented a certain new, original, and ornamental Design for an Electric-Lighting Fixture, of which the following is a specification.

In the accompanying drawing, the figure is

a view in side elevation showing my new design as applied to a lighting fixture.

What I claim is:—

The ornamental design for an electric lighting fixture, substantially as shown in the accompanying drawing.

SAMUEL H. SHIMINSKY.
